UNITED STATES PATENT OFFICE.

ANGELO DELSIMONE, OF NEW YORK, N. Y.

FOUNTAIN MARKER.

Application filed November 16, 1923. Serial No. 675,068.

To all whom it may concern:

Be it known that I, ANGELO DELSIMONE, a citizen of the United States, and resident of New York city, in the county of Kings and 5 State of New York, have invented certain new and useful Improvements in Fountain Markers, of which the following is a specification.

My invention relates to improvements in 10 the class of devices adapted for marking boxes, packages, barrels and the like, and has for its objects to provide simple and efficient means to control the flow of marking fluid to the marking member, as well as 15 to provide means for readily charging the barrel with marking fluid and to control the admission of air into the fountain or barrel of the device.

My invention comprises novel details of 20 improvement that will be more fully herein-after set forth and then pointed out in the claim.

Reference is to be had to the accompanying drawings forming a part hereof, where- 25 in—

Fig. 1 is a side elevation of my improved fountain marker;

Fig. 2 illustrates the barrel or fountain of the device;

30 Fig. 3 is a detail of the fluid outlet head at one end of the barrel;

Fig. 4 is a detail of the outlet valve;

Fig. 5 is a detail of the holder for the marking member;

35 Fig. 6 is a detail of the marking member;

Fig. 7 is a detail of the plug at the filling end of the barrel;

Fig. 8 is a detail of the stopper for said plug;

40 Fig. 9 is a detail of the air controlling valve, and

Fig. 10 is a sectional detail.

Similar numerals of reference indicate corresponding parts in the several views.

45 The barrel or fountain of the marker is indicated at 1, which may be in the form of a tube of suitable dimensions adapted to contain the marking fluid. At one end of the barrel or fountain is an outlet head 2, which may be of cast metal, and is shown provided with a rim portion 3 adapted to fit within the adjacent end of the barrel and which may be soldered thereto, or secured in any other way. Said head is shown pro- 50 vided with a recess 4 at its inner end which communicates with a longitudinal passage

5 opening through the outer end of the neck 4^a of the said head. The outer end of neck 4^a is shown having a recess at 6 to serve as a pocket or well for marking fluid received from the passage 5 which opens into recess 6. Said passage and recess are opposed to a marking member 7, which may be of felt or other suitable absorbent material, for marking the fluid upon the object to be marked. The member 7 is attached to the neck 4^a by means of a holder shown as a ferrule or sleeve 8 to receive said member in its bore and shown provided with prongs 8^a at one end to enter the member 7 to secure the same to the holder. The opposite end of the holder or ferrule is adapted to fit upon an adjacent outer end of neck 4^a, and said holder may fit said neck snugly and friction tight so that it 70 may be removed from the neck and replaced when a new marking member is to be used. The neck 4^a is provided with a transverse bore 4^b in which a valve or key 9 is fitted and which may be retained by a nut 10 80 on the threaded end of the valve or key, said valve or key being shown provided with a transverse bore 9^a for controlling the flow of fluid through the passage 5 into the marking head.

At the opposite end of the fountain or barrel is a plug 11, which may be secured within the end of the barrel by means of solder or in any other way. Said plug is shown provided with a passageway or bore 11^a having internal threads 12, and beyond said threads said plug is provided with a recessed opening through its end having a tapering or cone-like surface at 13 adapted to be engaged by a stopper 14 provided with an exterior cone-like surface 15 to engage the surface 13 to make a tight fit. The stopper 14 is provided with an extension having threads at 16 to engage the threads 12 of the plug, whereby the stopper may be detachably fitted to said plug. The stopper 14 is provided with a longitudinal bore 17 preferably having a relatively small outlet at 18. The bore 17 at the opposite end is provided with screw threads 19 to receive a screw 20. The outer end of bore 17 is provided with a tapering or cone-like surface 21 to receive a corresponding tapering or cone-like surface 20^a on screw 20, whereby a tight fit may be made to exclude air.

When my improved marker is to be charged with marking fluid the stopper 14

may be unscrewed from the plug 11, and the barrel or fountain may be charged through the bore in said plug. The stopper will then be replaced and the screw 20 will be fitted 5 tight against the stopper to prevent the entrance of air. When the marker is to be used the valve or key 9 will be adjusted to register its bore 9^a with a passage 5 and the screw 20 will be removed or loosened to permit 10 the entrance of air through bore 17 into the barrel. The marking fluid will pass through passage 5 into the marking member 7 and will accumulate in the recess or well 6, whereby the absorbent member 7 will be supplied 15 with marking fluid for marking barrels, boxes and other articles. When my improved fountain marker is not in use the valve or key 9 will be turned to stop the flow of fluid through passage 5 to member 7 and the screw 20 will be screwed in with its surface 20^a tight against the surface 21 to exclude 20 the entrance of air and prevent leakage of the fluid.

A cap 22 may be detachably applied upon the operating end of the marker to enclose 25 the marking head, valve and associate parts.

My improved fountain marker is relatively cheap to manufacture, convenient in use and not liable to get out of order.

Changes may be made in the details of 30 construction set forth, within the scope of the appended claim, without departing from the spirit of my invention.

Having now described my invention what I claim is:—

A fountain marker comprising a barrel provided with a head having an outlet passage, a valve to control the passage, a marking member carried by said head, a filling plug at the opposite end of the barrel, a 40 stopper cooperating with said plug, means to detachably retain the stopper in the plug, said plug having an air passage, and means to control said passage.

ANGELO DELSIMONE.
